UNITED STATES PATENT OFFICE

2,518,437

FLASHLIGHT

Walter R. Amstutz, Chicago, Ill., assignor to Butler Brothers, Chicago, Ill., a corporation of Illinois

Application August 23, 1947, Serial No. 770,244

7 Claims. (Cl. 240—10.68)

1

This invention relates to a flashlight and particularly to the details of construction thereof whereby a flashlight that is less expensive to manufacture results from design features which embody the invention described in the following specification.

One object of the invention is to provide a flashlight housing and a cover member therefor which is formed of transparent plastic material, the cover member having a reflector portion which is concave in the usual manner of reflectors and on which mirror silver has been deposited by recently developed precipitation plating processes capable of providing a coating of silver or other metal on plastic material, the flashlight thereby eliminating the necessity of a silvered reflector as a separate unit and a cover lens therefor to protect the silvered surface from the atmosphere, the silvered surface in the case of my invention being protected by the plastic itself by reason of the silvering being applied on the inner surface of the plastic covering.

Another object is to provide a cup-like protector for the silvered surface which seals in the back of the cover member thus protecting the silvered surface from being scratched or otherwise mechanically damaged when the cover member is off the housing of the flashlight, the cup-like member also serving as a means to support a prefocused flashlight bulb which projects into the reflector portion of the cover member.

Still another object is to provide a novel connecting means for the cover member in relation to the flashlight housing which comprises a bayonet joint type of connection, a portion of which is formed by the cup-like member and such portion also serving in conjunction with a special shape or bayonet slot to cooperate with contact springs in such manner as to provide a combined cover housing, connecting means and electric switch, the switch being operated by rotating the cover member relative to the housing, the degree of rotation being limited to off and on positions by the design of the bayonet connection. This switching arrangement eliminates the unsightliness of a separate switch projecting from the side of the flashlight housing and which type of switch presents a considerable percentage of expense in connection with the type of flashlight heretofore manufactured.

A further object is to provide a spring within the flashlight housing which biases the dry cells therein into contact with the flashlight bulb, and through the bulb, the cover member and the cup member serves as a means to hold the bayonet

2

slot connection in normally connected position and capable of manual disconnection only by pressing the cover member toward the housing against the bias of the spring.

Still a further object is to provide an electrical connection between the spring which contacts one end of the battery and the cup member which is electrically connected with one terminal of the flashlight bulb, in the form of a U-shaped strip of metal, the terminal ends of which are positioned to be engaged by lugs struck from the cup-like member, which lugs are selectively brought into and out of engagement with these terminal ends by oscillation of the cover member relative to the housing, the housing being provided with a pair of longitudinally extending grooves in which the U-shaped strip of metal is seated to hold it in position against rotation and to accommodate it so that it does not interfere with the positioning of dry cells in the housing.

With these and other objects in view, my invention consists in the construction, arrangement, and combination of the various parts of my device whereby the objects contemplated are attained, as hereinafter more fully set forth, pointed out in my claims, and illustrated in the accompanying drawings, wherein:

Figure 1 is a side elevation with portions broken away showing a flashlight embodying my present invention.

Figure 2 is a longitudinal sectional view thereof.

Figure 3 is a sectional view on the line 3—3 of Figure 2.

Figure 4 is a partial sectional view of the front end of the housing and cover showing them separated, and

Figure 5 is a rear elevation of the cover with the cup member removed therefrom in order to illustrate the silvered portion of the cover, which portion constitutes a reflector for the flashlight bulb.

On the accompanying drawing I have used the reference character H to indicate in general a flashlight housing and C a cover therefor. The housing H has a tubular portion 10, an enlarged flanged-like portion 12 and a tubular portion 14 somewhat larger than the tubular portion 10. The rear end of the housing terminates in a dome-like closure 16.

The cover C comprises a cylindrical portion 18 having ribs 20 to serve as knurling for rotating the cover on the housing and a concave portion 22 terminating in an opening 24 for a flashlight bulb 26. The cylindrical portion 18 is

adapted to fit over the cylindrical portion 14 and rotate thereon. The concave portion 22 is adapted to act as a reflector for the bulb 26, the inner surface of the portion 22 being silvered as indicated at 28 for this purpose.

The material of the housing H and the cover C is preferably plastic, the cover C being transparent with the housing H opaque, translucent, or transparent as desired. By having the cover C transparent, the silvering at 28 forms a reflector for the flashlight bulb 26 and, at the same time, the material of the cover protects the silvering from the atmosphere. Recent processes have been developed for plating metal such as plating or depositing by precipitation silver on plastic materials and these processes will enable me to provide a combined cover and reflector thus silvered.

The protection afforded by the plastic material eliminates the necessity of a cover lens and a rim to hold it in position as found in most flashlights thus reducing costs considerably.

To enhance the appearance of the flashlight in general the silvering may extend as at 30 (see Figures 2, 4, and 5) along the inner surface of the cylindrical portion 16 of the cover C. It is then enclosed by a cup-like closure member 32 formed of metal and having an annular flange 34 press fitted into the cover member. The center of the cup-like member 32 terminates in a cylindrical flange 36 and an inturned flange 38. The flange 38 is adapted to have the mounting flange 39 of the bulb 26 secured thereto in any suitable manner, this bulb being preferably of the prefocused type so that the flange 39 definitely determines the position of the filament of the bulb in relation to the reflector surface 28 for proper focusing of the light rays from the flashlight.

To connect the cover member C to the housing H, I provide inturned bayonet lugs 40 on the cylindrical flange 34 of the cup-like closure member 32 adapted to enter bayonet slots in the flange 14. Each of these slots has three distinct portions, an entry portion 42 extending axially, a locking portion 44 extending circumferentially and a constricted portion 46 connecting the portions 42 and 44. The length of the locking portion 44 is somewhat longer than the width of the bayonet lugs 40, the purpose of which will hereinafter appear.

The housing H is provided with a plurality of longitudinally extending ribs 48 which on the inside of the housing form longitudinally extending grooves 50. The ribs serve as a grip to hold the housing while using the flashlight or while rotating the cover member C relative to the housing.

Two of the grooves 50 serve to receive a U-shaped strip of metal 52 which is riveted at 54 in the housing portion 16 and has its terminal ends indicated at 56 twisted slightly as best shown in Figure 3. A spring 58 is interposed between the riveted end of the strip of metal 52 and a flashlight cell 60, and a second cell 62 is located in the housing H so that the two cells are in series in the usual manner. The central electrode 64 of the cell 62 engages the base contact 66 of the flashlight bulb 26.

Practical operation

In the operation of my flashlight, assuming the parts connected together as in Figure 1, it will be noted that the contact lugs 40 are adjacent the lower end of the bayonet slot portion 44 and stopped by a projection 45 of the slot. The lugs are in the position illustrated in Figure 3, that is,

out of engagement with the terminal ends 56 of the U-shaped strip 52. Thus the circuit to the bulb 26 is broken.

To turn the flashlight "on" the cover C is rotated clockwise relative to the housing H which is illustrated by dot and dash lines in Figure 3, the direction of rotation being indicated by the arrow a. In this dot and dash position, it will be noted that the lugs for engaging the contacts 56 are sprung inward slightly, thus establishing a circuit between the two. The complete circuit may now be traced from the rear end of the cell 60 through the spring 58 and the U-shaped strip 52 across the contacts 56 and 40 to the cup 32 and through the cup to the flange 40 which is one terminal of the flashlight bulb 26. The current then flows through the filament of the bulb and back through its base contact 66 to the center electrode 64 of the cell 62.

When it is desirable to open the flashlight for renewing the cells therein, the cover member C is pushed toward the housing H to take up the space shown in Figures 1 and 2 between the rear edge of the cylindrical portion 16 of the cover and the flange 12 of the housing. This positions the contact lugs 40 in alignment with the restricted portions 46 of the bayonet slots so that the lugs can be brought by counterclockwise rotation into alignment with the portions 42 of the slots for withdrawal therethrough as the cover is removed from the housing. While the cover is removed, the cup member 32 protects the silvering 28 and 30 against mechanical damage. The cells 60 and 62 are now accessible for replacement after which the cover C may be replaced.

In Figure 4, it will be noted that the cell 62 is in a projected position, this being caused by the spring 58. When replacing the cover it is necessary to work against the bias of the spring in passing the lugs 40 through the slot portions 42 and getting them into the portions 46 of the bayonet slots. The spring then serves, in addition to maintaining proper relation between the flashlight cells and the bulb, to snap the lugs 40 into the wider portions 44 of the slots after which they will remain during normal "on" and "off" operations of the cover member.

From the foregoing specifications, it will be obvious that I have provided a flashlight construction in which manufacturing costs are considerably reduced by providing a reflector silvering arrangement that eliminates some parts and providing other parts which serve multiple purposes, thus eliminating parts and the time required to assemble them in the manufacture of a flashlight. The cover connecting means serves also as a switch mechanism and the spring 58 serves to keep the cover assembled on the housing in addition to its normal function of engaging the dry cells with the flashlight bulb. The resulting structure is neat in appearance particularly by eliminating the unsightly switch normally provided on the housing, and is convenient to operate and open for the renewal of flashlight cells.

Some changes may be made in the construction and arrangement of the parts of my device without departing from the real spirit and purpose of my invention, and it is my intention to cover by my claims any modified forms of structure or use of mechanical equivalents which may be reasonably included within their scope.

I claim as my invention:

1. In a flashlight, a housing, a cover for the front end of said housing, said cover being formed of transparent plastic material with a concave

portion in which a flashlight bulb is adapted to be located, the back of said concave portion being silvered to provide a reflector for said flashlight bulb, and a cup-like closure member inserted in the back of said cover for enclosing the silvering therein, such silvering also extending along the inner surface of said cover member from the periphery of said reflector to said closure member.

2. In a flashlight, a housing, a cover member for the front end of said housing, said cover member being formed of transparent material with a concave portion in which a flashlight bulb is adapted to be focused, the back of said concave portion being silvered to provide a reflector for said flashlight bulb, a cup-like closure member inserted in the back of said cover member for enclosing the silvering therein, said cover member being telescopically mounted on said front end of said housing and rotatable relative thereto, a bayonet slot and lug connection between the two, said slot being arranged to permit limited movement of said lug and thereby limited rotation of said cover member on said housing, said cover member and housing having cooperating contacts in the flashlight circuit which engage at one limit of rotation and disengage at the other limit of rotation.

3. In a flashlight, a housing, a cover for the front end of said housing, said cover being telescopically mounted on said housing and rotatable relative thereto, a bayonet slot and lug connection between the two, said slot being arranged to permit limited rotation of said cover on said housing, said cover and housing having cooperating contacts in the flashlight circuit which engage at one limit of rotation and disengage at the other limit of rotation, said cover being formed of transparent plastic material with a concave portion in which a flashlight bulb is adapted to be located, the back of said concave portion being silvered to provide a reflector for said flashlight bulb.

4. In a flashlight, a housing, a cover member rotatable on the forward end and removable from said end, a closure member in said cover member having bayonet lugs, said forward end of said housing having bayonet slots to receive the same, a U-shaped contact strip electrically connected with a flashlight battery in said housing and having its terminal ends extended into the path of movement of said bayonet lugs, a flashlight bulb supported by said closure member and electrically connected thereby through said lugs with said contact strip in one position or rotation of the lugs in relation to the bayonet slots, said cover member having a reflector-shaped portion for said flashlight bulb and being silvered on its interior surface to provide a reflector surface therefor, said closure member enclosing said silvered surface when said cover member is removed from said housing.

5. A flashlight housing, a cover member rotatable on the forward end and removable from said end, bayonet lugs carried by said cover

member, said forward end of said housing having bayonet slots to receive said lugs, a U-shaped contact spring electrically connected with a flashlight battery in said housing and having its terminal ends yieldingly extended into the path of movement of said bayonet lugs, and a flashlight bulb supported by said cover member, said cover member having a reflector-shaped portion for said flashlight bulb, said reflector-shaped portion being transparent and being silvered on its interior surface to provide a reflector surface therefor.

6. In a flashlight, a housing, a cover for the front end of the housing, said cover being formed of a single transparent piece and having a rear tubular portion for securing the cover to the housing and an outwardly facing concave portion at the front, said concave portion being silvered on its back surface to provide a reflector, said concave portion having a central opening through which a flashlight bulb may extend to a focussed position in the concave portion and reflector, and a cup-like closure member in said tubular portion in rear of said concave portion for enclosing the silvering thereon.

7. In a structure of the character disclosed, a housing, a cover member for the forward end thereof, said cover member being telescopically mounted on said forward end and rotatable relative thereto, said housing having a bayonet slot adjacent its forward end, said slot having an axially extending entry portion, a circumferentially extending locking portion, and an axially rearwardly extending projection between said portions defining a constricted portion between the other portions of the slot, said cover member having a lug insertible into said slot, said cover member having a normal, forwardly biased position wherein said lug is engageable with said projection and with the opposite end of the locking portion of the slot at opposite limits of rotation of the cover member, said cover member and housing having cooperating contacts in the flashlight circuit which engage at one limit and disengage at the other limit of rotation of the cover member, a flashlight bulb supported by said cover member, and flashlight cells and a spring interposed between said housing and said bulb, said spring, acting through said cells and bulb, being operative to bias said cover member forwardly to said normal position.
